UNITED STATES PATENT OFFICE.

JOHN SZUTH, OF NEW YORK, N. Y., ASSIGNOR OF ONE-FOURTH TO GEZA KOCSIS, OF NEW YORK, N. Y.

FOLDING CRATE.

1,110,726.

Specification of Letters Patent. Patented Sept. 15, 1914.

Application filed July 11, 1913. Serial No. 778,587.

To all whom it may concern:

Be it known that I, JOHN SZUTH, a subject of the Emperor of Austria-Hungary, and resident of New York, in the county of New 5 York and State of New York, have invented certain new and useful Improvements in Folding Crates, of which the following is a specification.

This invention relates to folding crates 10 and devices comprising boxes and coops which may be shipped with their contents in an expanded shape, but collapsed into a folded condition of limited dimensions to be re-shipped to the consignor.

15 The invention consists of hinged sides, bottom and lid, so arranged that they may be folded upon one another to produce a package of very limited bulk and when expanded may be arranged to carry poultry, 20 vegetables or fruit and form a substantial packing device as will be more fully described in the following specification, set forth in the claims and illustrated in the drawings, wherein:

25 Figure 1, is a plan view of the crate with the lid thrown back. Fig. 2, shows the crate in its folded position. Fig. 3, is a vertical longitudinal sectional view. Fig. 4, is a cross sectional view.

30 The crate may be for the purpose of shipping vegetables, chickens, eggs, &c., and its sides made either of slats or boards to provide for the contents, but the drawings show a box made of boards hinged together and 35 having a partition to brace and strengthen same. The box is made up of side pieces 5, ends 6, top 7, and bottom 8, and hinged to the side pieces and between them is the partition 9. The end and side pieces are con-

40 nected together by interior hinges 10, and 11, the hinges being arranged so that the end pieces 6, lap over the edges of the side pieces but one set opens while the other closes in the act of collapsing the crate. When the 45 crate is opened in its operative form as shown in Figs. 1, 3 and 4, the bottom 8, fits in between the end pieces and against the partition and is held in this position by means of a catch 12, on the partition which 50 engages the bottom, firmly bracing these two

members of the box and preventing the collapse of the sides. The top is also held between the end pieces and a slot 13, receives a staple or hasp 14 secured to the partition and which may receive a pad lock to retain 55 the lid in its closed position. The hinges and the catch are thus all within the crate so that they cannot be tampered with from the outside and the box opened except by means of a key for the pad-lock. When it is 60 desired, however, to collapse and fold the box for re-shipping or storing and to economize in space, the catch 12, is disconnected after the lid has been thrown back on the rear side, the bottom is folded on the front 65 side and the sides and ends are shifted to bring them into the position shown in Fig. 2. On the upper and lower edge of the respective side pieces are pivoted fingers 15 and 16 and when the crate is folded these fingers 70 are turned at right angles to the sides so that they come in the path of hooks 17 and 18 on the lid and bottom respectively so as to retain the parts of the box in their folded 75 positions. The ends of the fingers are indented for the hooks 17 and 18 fit in them and prevent the parts from separating. The box is thus entirely without irregularities on its outside with the exception of the staple and pad-lock and no means is afforded by 80 which the contents of the box can be reached except after the lid is raised, nor can the box be collapsed except by the release of the catch 12. This catch may be any device connecting the bottom and partition but the 85 simple means shown in the drawing may be best for the purpose.

It is obvious that the details may be modified or the parts otherwise arranged without departing from the essential features above 90 described.

What I claim as new and desire to secure by Letters Patent, is:

1. In folding crates, the combination with sides, end pieces, bottom, top and partition 95 adapted to fold upon each other, of pivoted fingers on the edges of the sides, and hooks on the top and bottom to engage the fingers when the crate is folded.
2. In folding crates, the combination with 100

end pieces of sides; top and bottom hinged to the sides and fitting between the end pieces, a partition hinged to a side, a catch connecting the partition with the bottom, 5 fingers on the edges of the sides, and hooks on the top and bottom to engage the fingers when the crate is folded.

Signed at New York in the county of New York and State of New York this 19th day of June A. D. 1913.

JOHN SZUTH.
